CLAIM

The ornamental design for an insufflation circuit assembly, as shown and described.

DESCRIPTION

FIG. 1 is a top, front and right side perspective view of an insufflation circuit assembly embodying our new design.

FIG. 2 is a bottom, rear and left side perspective view thereof.

FIG. 3 is a front view thereof.

FIG. 4 is a rear view thereof.

FIG. 5 is a top view thereof.

FIG. 6 is a bottom view thereof.

FIG. 7 is a right side view thereof; and,

FIG. 8 is a left side view thereof.

Where utilized, broken lines are used to illustrate features of the insufflation circuit assembly that form no part of the claimed design.
